STORAGE VESSEL

Reign C. Ulm, Schererville, Ind., assignor to Union Tank Car Company, Chicago, Ill., a corporation of New Jersey

Filed Feb. 13, 1961, Ser. No. 63,922

Term of patent 14 years

(Cl. D91—1)

FIG. 1

FIG. 3

FIG. 1 is a perspective view of a storage vessel embodying my new design;

FIG. 2 is a top plan view of the storage vessel of FIG. 1; and

FIG. 3 is a fragmentary sectional view of the storage vessel of FIG. 1.

The characteristic features of my design for a storage vessel reside in the configuration of the corners in proportional relationship to the sides and roof of the vessel, as best shown in FIGS. 1 and 2.

I claim:

The ornamental design for a storage vessel, substantially as shown and described.
